UNITED STATES PATENT OFFICE

119,854

DESIGN FOR A LIGHT FIXTURE

Fred G. Gross, Chicago, Ill.

Application March 2, 1938, Serial No. 75,541

Term of patent 7 years

To all whom it may concern:

Be it known that I, Fred G. Gross, a citizen of the United States, residing at Chicago, in the county of Cook and State of Illinois, have invented a new, original, and ornamental Design for a Light Fixture, of which the following is a specification, reference being had to the accompanying drawing, forming part thereof.

Figure 1 is a plan view of a light fixture showing my new design.

Figure 2 is an end view thereof.

The design is characterized by a translucent cylindrical globe of a length substantially greater

than the diameter and with reduced ends, both closed by identical caps and finials at the outer ends of the caps, each cap fitting over the reduced portion and being of no greater outer diameter than the globe and tapered toward the end of a succession of circular steps of diminishing lengths and diameters, and the finials having similar steps diminishing in diameter toward the outer ends thereof.

I claim:

The ornamental design for a light fixture, as shown and described.

FRED G. GROSS,
